CLAIM

The ornamental design for a packaging container, as shown and described.

DESCRIPTION

FIG. 1 is a perspective view of the packaging container showing my new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a side elevational view thereof.

FIG. 7 is a cross sectional view taken along line 7-7 of FIG. 2.

FIG. 8 is a cross sectional view taken along line 8-8 of FIG. 2.

FIG. 9 is a cross sectional view taken along line 9-9 of FIG. 2; and,

FIG. 10 is a perspective view shown with the cap removed. The broken lines are included for the purpose of illustrating the interior portions that form no part of the claimed design.
